UNITED STATES PATENT OFFICE.

ALLEN NEWELL, OF GUADALAJARA, MEXICO.

RAILWAY-TIE AND RAIL-FASTENING.

No. 851,551.

Specification of Letters Patent.

Patented April 23, 1907.

Application filed December 13, 1906. Serial No. 347,827.

To all whom it may concern:

Be it known that I, ALLEN NEWELL, a citizen of the United States, and a resident of Guadalajara, Mexico, have invented a new and Improved Railway-Tie and Rail-Fastening, of which the following is a full, clear, and exact description.

This invention relates to improvements in metal ties for railways and rail fastenings, the object being to provide a metal tie that will be comparatively light, yet strong and serviceable, and further to provide a novel form of rail fastener that may be readily adjusted to the rail and normally hold the same from any lateral movement with relation to the tie.

I will describe a railway tie and rail fastening embodying my invention and then point out the novel features in the appended claims.

Reference is to be had to the accompanying drawings forming a part of this specification, in which similar characters of reference indicate corresponding parts in all the figures.

Figure 1 is a sectional elevation showing a portion of a tie and a rail fastening embodying my invention; Fig. 2 is a section on the line 2—2 of Fig. 1; Fig. 3 is a section on the line 3—3 of Fig. 2; and Fig. 4 is a section showing a modification.

The tie is of trough shape; that is, it has opposite side walls 5 extended upward from the base wall 6 and at the upper edges the side walls are provided with recesses 7 for receiving the base flange 8 of a rail 9.

The rail fastening consists of hook members 10, 11, the hook member 10 being designed to engage with one side of the rail flange, while the hook member 11 engages with the other side of the flange, as clearly indicated in the drawings. It will be noted that the hook portions 10 and 11 are arched on the outer side, making the parts which engage the rail flanges a little thicker from the inner 45 to the outer sides between the ends connecting with the shank to about the center, than the thickness from the last named point to the ends. The shank 12 of the hook member 10 is bifurcated or has two sections 13, 14 spaced apart and mounted to swing on a rod 15 extended through openings in the side walls 5 of the tie and near the bottom thereof, the object of which will hereinafter appear. The shank portion 16 of the hook 11 55 passes between the parts 13 and 14 of the hook shank 12 and is also mounted to swing

on said rod or bolt 15, and the several shanks are held in central position by means of washers 17 on the rod or bolt between said parts 13 and 14 and the inner surfaces of the 60 side walls 5.

From the pivotal point of the shank 12 arms 18 extend upward and straddle the shank 16, and a single arm 19 extends upward from the pivotal point of said shank 16, 65 the said arm 19 passing between the members 13 and 14 of the shank 12. These upwardly extended arms are arranged at an acute angle with relation to said shank portions, and the inner sides of the arms are 70 somewhat divergent to receive a fastening wedge 20 the ends of which engage with the inner sides of the tie walls 5, as indicated in Fig. 2. This wedge is held in place by means of a key 21 which passes through openings in 75 said side walls of the tie, and when inserted the smaller end of the key is turned downward against the outer side of one of said side walls 5, it being understood that this key is longitudinally tapered so that it will hold 80 tightly in the openings formed in the side walls and the tie. In Fig. 4 the key 22 is somewhat thicker in a vertical direction than the key 21, and in this example of my improvement one of the openings in the side 85 walls of the tie is sufficiently large to permit the passing therethrough of a wedge 23, and in passing the wedge through one of the openings it falls into place between the upwardly extended arms, and then the key is to be inserted.

By placing the rod or bolt 15 near the bottom of the tie, the fastening devices have a much greater arc of swing than would be possible were the pivotal point arranged in a 95 higher plane and thus the hooks which are forced inward by the spreading apart of the arms, will have a greater pressure on the rail flange. By bifurcating one of the shanks and placing the shank of the opposite hook between the bifurcated sections, the two hooks will engage with the flange, one directly opposite the other.

Having thus described my invention, I claim as new and desire to secure by Letters 105 Patent:

1. A metal railway tie having upwardly extended side walls for supporting the flange of a rail, and hook members having swinging connection with the tie for engaging with the base flange of a rail and means for forcing the hook members toward the rail.

2. A metal railway tie having a base wall and vertical side walls, a bolt extended through the side walls near the base wall, and rail fastening devices mounted to swing on said bolt and having hook portions for engaging with the rail flanges and means for forcing the hook members toward the rail. 5
3. A metal railway tie having upwardly extended side walls, a bolt extended through the side walls near the bottom, a rail fastener comprising a hook member having a bifurcated shank mounted to swing on said bolt and another hook member having a shank extended between the parts of the first-named shank and arranged to swing on said bolt, arms extended upward from the shanks and at an acute angle thereto, and a wedge for engaging between said arms. 10
4. A metal railway tie having upwardly extended side walls, a bolt extended between the side walls at the lower portion, a rail fastening comprising a hook having a bifurcated shank portion mounted to swing on said bolt and having upwardly extended arms, another hook portion having a shank mounted to swing on the bolt between the parts of the first-named shank, the flange-engaging hook members being of varying thickness from the inner to the outer sides, an arm extended upward from said last-named shank, a wedge for engaging between the arms, and a key for engaging with the wedge. 15
5. A metal railway tie having upwardly extended side walls, a bolt extended between the side walls at the lower portion, the said side walls having openings above the bolt, a rail fastener having a hook member for engaging with the flange of a rail, the said hook member having a bifurcated shank having swinging connection with the bolt, arms extended upward from the shank members, another hook for engaging with the rail flange and having a shank portion mounted to swing on the bolt between the members of the first-named shank, an arm extended upward from the last-named shank, a wedge for engaging between the arms of the opposite shanks, and a key adapted to pass through the openings of the tie side walls above the wedge, the said key being longitudinally tapered and having its smaller end turned downward against the outer side of one of the walls of the tie. 20
6. A metal railway tie for supporting the flange of a rail, hook members having swinging connection with the tie for engaging with the base flange of a rail, and means for forcing the hook members toward the rail. 25

In testimony whereof I have signed my name to this specification in the presence of two subscribing witnesses.

ALLEN NEWELL.
